UNITED STATES PATENT OFFICE.

EDWARD F. BURTIS, OF SACRAMENTO, CALIFORNIA.

CARRIAGE-JACK.

SPECIFICATION forming part of Letters Patent No. 404,167, dated May 28, 1889.

Application filed December 4, 1888. Serial No. 292,664. (No model.)

To all whom it may concern:

Be it known that I, EDWARD F. BURTIS, of Sacramento, Sacramento county, State of California, have invented an Improvement in Car-
5 riage-Jacks; and I hereby declare the follow-
ing to be a full, clear, and exact description
of the same.

My invention relates to the general class of
10 lifting-jacks, and especially to those designed
for use with wagons, carriages, and other ve-
hicles, and in which is employed a bowed arm
having a bearing at one end on top of the axle,
and having in its other end a rod or bar form-
15 ing an inserted continuation of the spindle of
the vehicle-axle; and my invention consists,
in connection with a carriage-jack of this de-
scription, of a novel nut-remover, hereinafter
described.

The object of my invention is to provide, in
20 connection with the bowed arm and inserted
continuation of the axle-spindle of jacks of
this description, a simple and effective device
for readily removing the nut from the end of
25 the axle-spindle, whereby the wheel may be
moved off of the spindle onto the continua-
tion-bar of the jack.

Referring to the accompanying drawings
30 for a more complete explanation of my inven-
tion, Figure 1 is an elevation of my jack show-
ing the first engagement of the nut-remover.
Fig. 2 is a view showing the nut removed and
35 the wheel drawn off the axle-spindle. Fig. 3
is a perspective detail.

A is the bowed arm of the jack, which passes
35 through between the spokes of the wheel W
of the vehicle, and has at its inner end a forked
bearing, a, which rests on top of the vehicle-
axle X. Securely fixed in the outer end of
40 the bowed arm and extending inwardly is a
rod or bar, B, which forms the continuation
of the axle-spindle x. This rod or bar has a
beveled concaved end, b, provided internally
45 with threads which correspond to the threads
of the axle-spindle, and when said end is fit-
ted under the axle-spindle the threads mesh
and thus form a temporary joint, the spindle
being supported upon the end of the rod or
50 bar B.

C is a handle, which in this case is made
55 tubular, and through this tubular handle is
passed the stem D of the nut-remover, said
stem having on its outer end the handle d, by

which it is rotated. With the inner end of
the stem D is connected the wrench E. This
consists of an ordinary four - sided piece 55
adapted to fit over the nut Y of the axle-
spindle, and is provided on its back with arms
e, which embrace the end of the stem, and are
pivoted thereto by a pin, e', so that said
wrench may have a movement up and down 60
about said pin as a center. These arms are
carried down below the pivotal center and
form bearings e².

The beveled end b of the axle rod or bar B
is provided on each side with inclined planes 65
or tracks b', which form cams against which
the bearing ends e² of the arms e of the wrench
are adapted to come in contact, and on which
they travel for the purpose of throwing the
wrench and the nut which it contains up- 70
wardly when the wrench is drawn back, so
that the nut will not drop out of the wrench.
The back edges of the wrench are slightly
rounded or beveled, so that they will not in-
terfere with the end of the rod or spindle B. 75

The operation of the jack is as follows: The
bowed arm A is passed through between the
spokes of the wheel, and its forked inner end
bears upon the top of the axle. The stem D
is then moved longitudinally until the wrench 8c
on its end fits over the nut of the axle-spindle.
Said stem is now rotated so that the wrench
unscrews the nut, whereupon the stem is re-
tracted longitudinally, and the bearing ends
e² of the wrench, coming in contact with the 85
inclined planes or cams b' on each side of the
axle-rod B, turn the wrench with its nut to a
slightly-upward position, so that the nut is
prevented from falling out of the wrench.
The beveled threaded end b of the axle-rod B 90
is now fitted under the threaded end of the
axle from which the nut is removed, and the
wheel is then drawn off onto said rod and
serves to support the whole device, as with
jacks of this kind. When the spindle is prop- 95
erly oiled and greased, the wheel is pushed
back onto it, the axle-rod B is withdrawn, and
the stem D is moved inwardly to put the nut
onto the spindle end, so that by turning the
stem the nut is replaced. 100

Having thus described my invention, what I
claim as new, and desire to secure by Letters
Patent, is—

1. In a carriage-jack, and in combination

with the bowed arm A and the axle rod or bar B thereof, a longitudinally-movable and rotary stem seated in the bowed arm and having a wrench upon its end adapted to fit 5 the nut of the axle-spindle, substantially as herein described.

2. In a carriage-jack, and in combination with the bowed arm A and the axle rod or bar B thereof, the tubular handle C, the rotary and longitudinally-movable stem D, mounted in said handle, and the wrench E at the inner end of the stem, adapted to engage and remove the nut of the axle-spindle, substantially as herein described.

15 3. In a carriage-jack, the bowed arm A and the axle rod or bar B thereof, in combination with the longitudinally-movable and rotary stem D, seated in the bowed arm parallel with the axle rod or bar, and the wrench pivoted 20 to the inner end of the stem and adapted to engage the nut of the axle-spindle, said wrench having arms adapted to come in contact with cams on the axle rod or bar to turn it upwardly and hold the nut safely when removed, 25 substantially as herein described.

4. In a carriage-jack, the bowed arm A and the axle rod or bar B, having a beveled end, b, with inclined planes or cams b' on each side, in combination with the longitudinally- 30 movable and rotary stem D, seated in the

bowed arm, and the wrench E, having the arms e pivoted to the inner end of the stem, and projecting bearing ends e², adapted to come in contact with the inclined planes or cams b' of the axle rod or bar, whereby the 35 wrench is turned upwardly when retracted and holds the nut safely, substantially as herein described.

5. A carriage-jack comprising the bowed arm A, having the bearing a at its inner end 40 for resting on the axle, the rod or bar B, secured to its outer end and having a beveled end, b, adapted to bear under the axle-spindle and provided with inclined planes or cams b' on its sides, the tubular handle C, the stem 45 D, mounted in said handle and adapted to be moved longitudinally and rotated and having the handle d on its outer end, and the wrench E, having the arms e pivoted to the end of the stem D, with projecting bearing ends 50 e², adapted to come in contact with the inclined planes or cams b of the rod or bar B, substantially as herein described.

In witness whereof I have hereunto set my hand.

EDWARD F. BURTIS.
